UNITED STATES PATENT OFFICE.

MATHEW A. HANSE, OF BARNESVILLE, OHIO.

DESIGN FOR A PLATE OR SIMILAR ARTICLE.

Application filed July 21, 1928. Serial No. 27,555. Term of patent 3½ years.

To all whom it may concern:

Be it known that I, MATHEW A. HANSE, a citizen of the United States, residing at Barnesville, in the county of Belmont and State of Ohio, have invented a new, original, and ornamental Design for a Plate or Similar Article, of which the following is a specification, reference being had to the accompanying drawing, forming part thereof.

Fig. 1 shows a plan view of a plate, the ornamentation being omitted because of the reduced size of the figure; and,

Fig. 2 shows a plan view of a segment of the plate, for the purpose of clearly illustrating the details of the ornamentation. It is understood that this ornamentation is continued entirely around the rim of the plate.

I claim:

The ornamental design for a plate or similar article, as shown and described.

MATHEW A. HANSE.
